W. N. PEAK.

WALL PAPER.

No. 16,936.

Patented Oct. 12, 1886.

UNITED STATES PATENT OFFICE.

WILLIAM N. PEAK, OF BROOKLYN, NEW YORK.

DESIGN FOR WALL-PAPER.

SPECIFICATION forming part of Design No. 16,936, dated October 12, 1886.

Application filed August 20, 1886. Serial No. 211,437. Term of patent 3½ years.

To all whom it may concern:

Be it known that I, WILLIAM N. PEAK, of Brooklyn, in the county of Kings and State of New York, have invented a new and original 5 Design for Wall-Paper, of which the following is a specification.

The nature of my design is fully represented in the accompanying print, to which reference is made.

10 The design consists, principally, of the representation of the crown A, the spider-shaped figure B, the side scallops, C, and the border D. The crown is represented by parallel stripes a, b, and c, the complex stripe d between the stripes b c, and a crest composed of 15 two side members, e e, and a central member, f. The crown A, spider-shaped figure B, and the scallops C are outlined by stepped borders

g h, as shown in the accompanying print. The border D shows blocks i, a stripe, j, and 20 blocks k, and the intermediate small T-pieces, l, as shown in the accompanying print.

I claim—

1. The design for wall-paper herein shown and described, the same consisting of the 25 crown-shaped figure A and the spider-shaped figure B.
2. The design for wall-paper herein shown and described, the same consisting of a crown-shaped figure, A, a spider-shaped figure, B, 30 scallops C, and a border, D.

WILLIAM N. PEAK.
